UNITED STATES PATENT OFFICE.

DANIEL D. MILLER, OF NEW YORK, N. Y., ASSIGNOR TO WESTERN ELECTRIC COMPANY, INCORPORATED, OF NEW YORK, N. Y., A CORPORATION OF NEW YORK.

ELECTROMAGNETIC DEVICE.

1,339,778.

Specification of Letters Patent. Patented May 11, 1920.

Application filed December 10, 1917. Serial No. 206,455.

To all whom it may concern:

Be it known that I, DANIEL D. MILLER, a citizen of the United States, residing at New York, in the county of New York and State 5 of New York, have invented certain new and useful Improvements in Electromagnetic Devices, of which the following is a full, clear, concise, and exact description.

This invention relates to electromagnetic 10 devices and in particular to a sensitive polarizing relay especially suitable for use in connection with high speed telegraph apparatus.

With the present type of high speed relays 15 trouble is continually being experienced, due to the slight changes in adjustment, resulting from the use of constructions employing pivoted bearings and knife edges. In view of the small air gaps and delicate adjustments necessitated by the requirement of 20 high sensitiveness a very slight wear of the moving parts or a change in adjustment makes the relay inoperative and expert adjustment is required.

Again in connection with long loaded telephone lines which are used for telegraph work the presence of the loading coils makes it necessary to keep down the amplitude of 25 the telegraph or Morse currents in order to prevent making the lines noisy, and therefore for this service a relay is required 30 which is more sensitive than those ordinarily employed on long telegraph lines where the amplitude of the current is not necessarily limited.

It is, therefore, the object of the present 35 invention to provide a polarized relay of high sensitiveness and one in which the construction is such as to allow its use under 40 commercial conditions without requiring readjustment or expert attention. Another object is to provide a relay in which all of the adjustments may be made without interfering with or necessitating the removal of 45 the relay from its operating circuit. A further object is to provide a sensitive biasing arrangement which will permit of quick and accurate biasing of the armature. A still further object is to provide an armature 50 construction permitting a very high degree of sensitiveness.

To accomplish these objects a feature of the invention resides in the employment of a balanced magnetic circuit having the 55 armature fixed at one end, that is, an arma-

ture of the cantaliver beam type and balancing out the polarizing flux by the stiffness of the armature itself. Another feature consists in the employment of an armature biasing arrangement comprising a light flexible spring carried by the armature itself and adjustable means for flexing this spring in either direction. Still another feature 60 consists in reducing the cross section of the armature at a given point in order that its sensitiveness be not impaired when operating under the severe service conditions resulting from unequal positive and negative current impulses rapidly following each other.

Still other features will be brought out 65 more clearly in the following specification and in the accompanying drawing, in which Figure 1 is a perspective view of a relay embodying this invention; and Fig. 2 is a 70 plan view of certain parts of the structure.

Referring now to the drawing in which there is illustrated a relay embodying this 75 invention, there is shown a relay frame 4 of brass or other non-magnetic material, 80 this frame being equipped with standards or mounting lugs 5—5, provided with mounting holes 6—6, whereby the device may be attached to any suitable base. This frame is also provided with projections or bosses 85 7—7 for the purpose of supporting an adjusting device to be described hereinafter. Supported at one end of frame 4, and secured thereto by means of screws 8—8, are the pole pieces 9—9 of magnetic iron, and 90 which may be built up of thin sheets or laminations if the apparatus is to be operated by currents of very high frequencies. The armature 10 is rigidly clamped between the pole pieces 9—9, but separated therefrom by the non-magnetic shims 11—11. By 95 the use of these shims, high reluctance gaps are provided between the pole pieces 9—9 and the armature 10, thereby providing magnetic poles and fixed air-gaps where the 100 armature is clamped in position. As a result of this construction, the effects of residual magnetism are largely overcome and the desired balanced magnetic circuit is retained with its advantages of high sensitivity. The clamping screws 12—12 engage the threaded portions 13—13 of frame 4, being provided for clamping these parts together. After the clamping screws 12—12 are tightened, the screws 8—8, which pass 110

through oblong holes or slots in the pole pieces, are tightened, seating these parts securely upon the frame. Pins 14-14 of brass or other non-magnetic material are provided 5 to facilitate bringing the parts in correct alinement.

In order to make the operation of the relay more sensitive, as will be explained hereinafter, when operating with wave forms of 10 opposite polarity and of alternately high and low amplitude, the armature 10 is provided with notches 15-15, as shown, in order to cut down its cross section at this point.

15 One end of each of the pole pieces 9-9 is provided with a threaded hole adapted to engage the threads of the adjusting screws 16-16 which are of magnetic material and act as extensions to the pole pieces. Saw 20 slots 17-17 are also provided in the pole pieces, as shown, so that when the screws 16-16 are once adjusted they may be locked in position by tightening the screws 18-18.

The relay operating coil 19 is provided with 25 spoolheads 20-20, one of which has a slight angled projection permitting it to be securely fastened to the frame by means of the screw 21. The hollow core of this coil is so dimensioned as to allow ample clearance 30 for the operation of the armature 10. In alinement and on opposite sides of the armature are the contact screws 22-22 passing through threaded openings in the bracket members 23-23, which in turn are secured 35 to the frame 4 by means of screws 24-24, but are insulated therefrom by means of the insulating plates 25-25 and the insulating washers 26-26. A terminal clip 27-27 is provided at each bracket to facilitate making 40 the necessary connections. The brackets 23-23 are provided with saw slots 28-28 which coöperate with the screws 29-29 to permit locking the contact screws 22-22 securely in position after the adjustment is 45 once made. Each contact screw is fitted with a tip of platinum or other suitable contact material and is adapted upon vibration of the armature to engage the contact parts 30-30, which are of a similar material and 50 are securely fastened to the armature.

The means for polarizing this relay consists of a U-shaped permanent magnet 31, and a pair of polar extension members 32, only one of which is shown on the drawing. 55 These members are secured to the pole pieces 9-9 by means of screws 33-33. The ends of the magnet 31 are drawn against the lower end of polar extension members 32-32, by means of the clamping bar 34 which is 60 of brass or other suitable non-magnetic material. A stud 35 fastened at one end to the frame 4, passes through the hole in the clamping bar 34 and is threaded to receive a clamping nut which permits drawing the 65 parts together.

A screw 36 passing through a perforation in the relay frame 4 supports the closed end of the permanent magnet. In order to obtain the correct strength of permanent magnet, a slidable keeper 37 is provided to furnish a shunt path for a portion of the flux of the permanent magnet, the position of this keeper determining the amount of flux diverted from the magnetic circuit of the relay proper. The desired movement of 70 this keeper is brought about by turning the knurled head of the adjusting screw 38. This screw engages a threaded opening in the member 39, this member in turn being loosely pinned to the keeper in order to allow the latter to be drawn into intimate contact with the permanent magnet by the magnetizing force of the magnet itself.

In view of the small air gaps required on a relay of this type, it is practically impossible to locate the armature so that it will be perfectly balanced without resorting to some type of biasing arrangement. In the present case the biasing arrangement consists of a light, flexible spring 40, rigidly secured 85 to and in line with the armature, and an adjusting device which permits the supporting of the free end of spring 40 at either side and at a given position. This device consists of a rod 41 slidable through perforations in the bosses 7-7 and having one end grooved or otherwise shaped to prevent its rotation. The other end of this rod is threaded to engage the adjusting nut 42, the shouldered end of which is held against the 90 outside of the boss 7, by means of a helical spring 43 fitting over the recessed portion of the rod 41 and compressed between the shoulder portion of this rod and the inside of the boss. Secured to the rod 41 by means 95 of the screw 44 is a metal punching 45, one end of which is recessed to receive the free end of spring 40 and carries a pair of knife edges 46-46 separated by a distance slightly greater than the thickness of the spring 40 100 so as not to cause buckling of this spring. The other end of this punching acts as a pointer and registers with the calibrated 105 scale on the bracket piece 47, this bracket being secured to the bosses 7-7 by means of 110 the screws 48-48. A knurled-head thumb screw 49 is provided to lock the rod 41 in position after the adjustment is once made.

The high sensitivity of the structure just described will at once be apparent by considering its operation. With no current flowing through the energizing winding the flux from the permanent magnet exerts a pull on the armature in either direction but any movement of the armature is prevented 120 by the cantilever beam type of armature which is in a neutral position as regards the pole pieces. The stiffness of this armature however, is only slightly greater than is necessary to off-set the polarizing bias or the 125 130

pull exerted by the permanent magnet and therefore a very small flux generated in the armature by a current flowing through the energizing winding is sufficient to cause movement of the armature and the subsequent closure of the contact members. In any polarized relay the force tending to cause movement of the armature is the difference between the force due to the operating current and the biasing force due to the permanent magnet. The operating force, that is, the force due to the operating current flowing in the winding, is proportional to the product of the flux due to the ampere turns and the flux due to the permanent magnet. The biasing force, due to the permanent magnet, is proportional to the square of the permanent magnet flux. For these reasons it is highly desirable to make the polarizing flux large in order to obtain a sensitive piece of apparatus, but in the common type of pivoted relay this is not practical since the armature will normally be biased to one side or the other and the operating force must therefore be greater than the biasing force in order to cause movement of the armature. However, in the present structure, since the polarizing bias is practically counterbalanced mechanically by means of the cantaliver beam type of construction used, it is possible to obtain high sensitivity by increasing the polarizing flux. Still another advantage is gained by being able to increase the polarizing flux since it permits the working of the iron parts at the most favorable flux density. This construction also has a decided advantage in freedom from mechanical troubles inherent in structures which employ pivot bearings or knife edges.

Increased sensitivity under certain conditions also results from employing an armature provided with notches as shown in the structure described. Especially in telegraphic work it is often required to operate a relay with pulsations of opposite polarity. Under such conditions if a pulsation of one polarity and of high amplitude is immediately followed by a pulsation of the opposite polarity and low amplitude the sensitive operation of the relay depends quite largely upon the residual effect of the armature itself. The constricted portion of the armature brought about by employing the notches as shown aids in causing its demagnetization and therefore brings about greater sensitiveness under such conditions.

What is claimed is:

1. An electromagnetic device comprising a permanent magnet, an energizing coil, an armature extending therethrough, and means including said armature and exclu-

sive of said coil for counterbalancing the greater portion of the polarizing bias of said permanent magnet in either direction. 65

2. An electromagnetic device comprising an energizing coil, a permanent magnet having pole pieces therefor, and an armature supported between said pole pieces as a cantaliver beam and extending through the coil, said armature being so arranged and proportioned that the resistance of the beam to bending in either direction nearly counterbalances the polarizing bias of said permanent magnet. 70

3. An electromagnetic device comprising a polarizing magnet, a pair of bifurcated pole pieces for said magnet, each of said pole pieces comprising a fixed limb and an adjustable limb, an armature clamped between said fixed limbs, an energizing coil encircling said armature, a circuit changing device operated by said armature, and an armature biasing device. 80

4. An electromagnetic device comprising a permanent magnet, a pair of pole pieces for said magnet, each of said pole pieces comprising a fixed limb and an adjustable limb, an armature clamped between said fixed limbs and adapted to vibrate between said adjustable limbs, and an energizing coil encircling said armature. 85

5. An electromagnetic device comprising a permanent magnet, a pair of pole pieces for said magnet, each of said pole pieces comprising a fixed limb and an adjustable limb, an armature clamped between said fixed limbs, means for magnetically insulating said armature from said pole pieces, and an energizing coil encircling said armature. 95

6. An electromagnetic device comprising a permanent magnet, a pair of pole pieces for said magnet, each of said pole pieces comprising a fixed limb and an adjustable limb, means for locking said adjustable limbs in position, a cantaliver beam armature clamped between said fixed limbs and adapted to vibrate between said adjustable limbs, and an energizing coil encircling said armature. 105

7. An electromagnetic device comprising a permanent magnet, a pair of pole pieces for said magnet, each of said pole pieces comprising a fixed limb and an adjustable limb, an armature clamped between said fixed limbs and adapted to vibrate between said adjustable limbs, the cross section of said armature having a restricted portion intermediate its ends, and an energizing coil 115 encircling said armature.

8. An electromagnetic device comprising a permanent magnet, a pair of pole pieces for said magnet, each of said pole pieces

- 4
- 5 comprising a fixed limb and an adjustable limb, an armature clamped between said fixed limbs, means for positioning said pole pieces with respect to said armature, additional means for magnetically insulating 10 said armature from said pole pieces, and an energizing coil for said armature.
9. An electromagnetic device comprising a permanent magnet, a pair of bifurcated pole pieces for said magnet, each of said 15 pole pieces comprising a fixed limb and an adjustable limb, an armature clamped between said fixed limbs, means for magnetically insulating said armature from said pole pieces, a contact member carried by 20 said armature, a second contact member adapted to be engaged by said first contact member upon vibration of said armature, and an energizing coil for said armature.
10. An electromagnetic device comprising 25 a permanent magnet, a pair of bifurcated pole pieces for said magnet, each of said pole pieces comprising a fixed limb and an adjustable limb, an armature clamped between said fixed limbs, an energizing coil 30 encircling said armature, a circuit changing device operated by said armature, and an armature biasing device including a flexible extension for said armature, and a means for supporting the free end of said extension 35 member.
11. An electromagnetic device comprising a permanent magnet, a pair of bifurcated pole pieces for said magnet, each of said pole pieces comprising a fixed limb and an 40 adjustable limb, an armature clamped between said fixed limbs, an energizing coil encircling said armature, a circuit changing device operated by said armature, an 45 armature biasing device including a spring member attached to said armature in alignment therewith, and an adjustable means for supporting the free end of said spring member.
12. An electromagnetic device comprising 50 a permanent magnet, a pair of bifurcated pole pieces for said magnet, each of said pole pieces comprising a fixed limb and an adjustable limb, an armature clamped between said fixed limbs, an energizing coil encircling said armature, a circuit changing 55 device operated by said armature, an armature biasing device including a flexible spring member attached to said armature, a pair of knife edges separated from each other a distance slightly greater than the 60 thickness of said spring member, and means for adjusting the position of said knife edges.
13. An electromagnetic device comprising 65 a permanent magnet, a pair of bifurcated pole pieces for said magnet, each of said pole pieces comprising a fixed limb and an adjustable limb, an armature clamped between said fixed limbs, an energizing coil encircling said armature, a circuit changing 70 device operated by said armature, an armature biasing device including a spring member attached to said armature and in alignment therewith, adjustable means for supporting the free end of said spring member, a pointer carried by said adjustable means, and a scale registering with said 75 pointer in its movement.
- In witness whereof, I hereunto subscribe my name this 6th day of December, A. D. 1917.
- DANIEL D. MILLER.
